[57] CLAIM

The ornamental design for a wagon, as shown and described.

DESCRIPTION

FIG. 1 is a side elevational view of a wagon showing my new design, the side opposite being a mirror image thereof;

FIG. 2 is a rear elevational view thereof;

FIG. 3 is a front elevational view thereof;

FIG. 4 is a top plan view thereof;

FIG. 5 is a bottom plan view thereof;

FIG. 6 is a perspective view thereof;

FIG. 7 is a perspective view of a modified embodiment

of the design shown in FIGS. 1 through 6;

FIG. 8 is a side elevational view thereof, the side oppo-

site being a mirror image;

FIG. 9 is a rear elevational view thereof;

FIG. 10 is a front elevational view thereof;

FIG. 11 is a top plan view thereof; and

FIG. 12 is a bottom plan view thereof.
